[57] CLAIM

The ornamental design for a child's car seat shell, as shown and described.

DESCRIPTION

FIG. 1 is a perspective view of a child's car seat shell showing my new design, with a car seat shown in broken lines for purposes of illustration only and forming no part of the claimed design;

FIG. 2 is a top plan view thereof on a reduced scale;

FIG. 3 is a right side elevational view of FIG. 2; left side being a mirror image thereof;

FIG. 4 is a front elevational view of FIG. 2;

FIG. 5 is a rear elevational view of FIG. 2; and

FIG. 6 is a bottom plan view of FIG. 2.
